(57) **CLAIM**

The ornamental design for a laser diode, as shown and described.

DESCRIPTION

FIG. 1 is a front, right side, top perspective view of a laser diode according to a first embodiment of our new design;

FIG. 2 is a front view of the laser diode according to the first embodiment;

FIG. 3 is a rear view of the laser diode according to the first embodiment;

FIG. 4 is a top view of the laser diode according to the first embodiment, the bottom view being a mirror image thereof;

FIG. 5 is a right side view of the laser diode according to the first embodiment, the left side view being a mirror image thereof;

FIG. 6 is a front, right side, top perspective view of a laser diode according to a second embodiment of our new design;

FIG. 7 is a front view of the laser diode according to the second embodiment;

FIG. 8 is a rear view of the laser diode according to the second embodiment;

FIG. 9 is a top view of the laser diode according to the second embodiment, the bottom view being a mirror image thereof;

FIG. 10 is a right side view of the laser diode according to the second embodiment, the left side view being a mirror image thereof;

FIG. 11 is a front, right side, top perspective view of a laser diode according to a third embodiment of our new design;

FIG. 12 is a front view of the laser diode according to the third embodiment;

FIG. 13 is a rear view of the laser diode according to the third embodiment;

FIG. 14 is a top view of the laser diode according to the third embodiment, the bottom view being a mirror image thereof;

FIG. 15 is a right side view of the laser diode according to the third embodiment, the left side view being a mirror image thereof;

FIG. 16 is a front, right side, top perspective view of a laser diode according to a fourth embodiment of our new design;

FIG. 17 is a front view of the laser diode according to the fourth embodiment;

FIG. 18 is a rear view of the laser diode according to the fourth embodiment;

FIG. 19 is a top view of the laser diode according to the fourth embodiment, the bottom view being a mirror image thereof;

(Continued)

FIG. 20 is a right side view of the laser diode according to the fourth embodiment, the left side view being a mirror image thereof;

FIG. 21 is a front, right side, top perspective view of a laser diode according to a fifth embodiment of our new design; FIG. 22 is a front view of the laser diode according to the fifth embodiment;

FIG. 23 is a rear view of the laser diode according to the fifth embodiment;

FIG. 24 is a top view of the laser diode according to the fifth embodiment, the bottom view being a mirror image thereof; FIG. 25 is a right side view of the laser diode according to the fifth embodiment, the left side view being a mirror image thereof;

FIG. 26 is a front, right side, top perspective view of a laser diode according to a sixth embodiment of our new design; FIG. 27 is a front view of the laser diode according to the sixth embodiment;

FIG. 28 is a rear view of the laser diode according to the sixth embodiment;

FIG. 29 is a right side view of the laser diode according to the sixth embodiment; and,

FIG. 30 is a top view of the laser diode according to the sixth embodiment.

In each embodiment, the broken lines depict portions of the laser diode that form no part of the claimed design.
